CLAIM

The ornamental design for a bracket for optical network terminal, as shown and described.

DESCRIPTION

FIG. 1 is a front perspective view of a bracket for optical network terminal, showing my new design;

FIG. 2 is a rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof; and,

FIG. 9 is a front perspective view thereof, shown in a position for use with an environmental optical network terminal.

Broken lines seen in the drawings depict environmental subject matter and form no part of the claimed design.
